(57) **CLAIM**

The ornamental design for the header post support, as shown and described.

DESCRIPTION

FIG. 1 is a perspective view of the header post support in use.

FIG. 2 is a perspective view of the header post support alone.

FIG. 3 is a top plan view thereof.

FIG. 4 is a bottom plan view thereof.

FIG. 5 is a left side elevation view thereof, the right side elevation view being the same as said left side elevation view.

FIG. 6 is a front side elevation view thereof, the rear side elevation view being the same as said front side elevation view.

The broken lines shown in FIG. 1 are for illustrative purposes only and form no part of the claimed design.
